TAMPERPROOF CONTAINER FOR DISTILLED LIQUORS

Frank J. O'Brien, Pelham Manor, N. Y., assignor to Continental Can Company, Inc., New York, N. Y., a corporation of New York

Application April 26, 1934, Serial No. 722,582

2 Claims. (CL 206—46)

The invention relates to new and useful improvements in a tamper-proof container for distilled liquors or the like. Efforts have been made to produce a container for distilled liquors which cannot be tampered with, by providing a metal closure or receptacle which encloses the glass container, wherein the metal receptacle is so constructed that when once ruptured in order to give access to the glass bottle, then it cannot be reclosed. Difficulty has been experienced, however, in connection with the application of a revenue stamp to such a package. It must be attached to the glass bottle and at the same time it is essential that it shall be visible for inspection.

An object of the present invention is to provide a container for distilled liquors of the above type which is so constructed that the revenue stamp may be applied to the outer face of the metal receptacle, and also attached to the glass bottle container within said metal receptacle.

In the drawing:

Figure 1 is a view partly in side elevation and partly in section showing a container embodying the invention;

Fig. 2 is a plan view of the same; and

Fig. 3 is a side view of the neck and shoulder portion of the container.

The container for the distilled liquor includes an inner receptacle 1 which is of glass or other similar material. This glass container is provided with a curved shoulder portion 2 and a neck portion 3 which are of the usual construction. Surrounding and enclosing the inner glass receptacle is an outer metal receptacle consisting of a body portion 4 to which a top closure portion 5 is secured by a double seam 6. This top closure portion 5 is curved to conform to the curvature of the shoulder of the glass receptacle that is to be housed within the metal receptacle. Attached to the top closure portion 5 is a neck portion 7 which is secured to the top portion by a seam 8 formed by the interfolding of the metal parts. Attached to the upper portion of the neck portion is a disk 9 which is likewise secured to the neck portion by a seam 10 formed by the interfolding of the metal parts.

The glass container after it is filled with the distilled liquor and properly closed, is inserted through the bottom end of the metal receptacle, and after it is placed in the metal receptacle, then the bottom end closure 11 is secured to the body portion of the metal receptacle by a seam 12 formed by the interfolding of the metal parts.

This completes the housing of the bottle within the container. The neck portion 7 of the metal container is provided with score lines 13 and 14 which are spaced from each other to form a tearing strip. The tearing strip has a projecting tongue 15 on which a key may be placed for removing the tearing strip to sever the neck portion so that access may be had to the bottle neck for removing the seal therefrom. These score lines are placed well down on the neck portion so as to leave a considerable portion of the neck of the bottle exposed when the metal container is opened. This opening of the metal container does not provide a means whereby the bottle may be separated from the metal container. The container for distilled liquors, as described, is the invention of Jack M. Cross, and is disclosed in his application Serial No. 709,537, filed February 2, 1934.

The present invention has to do particularly with a means whereby the revenue stamp may be applied to the outer face of the metal container and at the same time attached to the bottle within the metal container so that said revenue stamp is visible for inspection, and at the same time, the bottle cannot be removed from the metal container without the rupturing of the revenue stamp. The invention as illustrated in the drawing, consists in the providing of the top portion 5 with openings 16 and 17. These openings are formed in the shoulder portion of the metal container and midway between the neck and the double seam 6. The glass container 1 has a lug 18 formed therein which is an integral part of the glass container, and this lug is so disposed that it projects through the opening 16. There is a similar lug 19 projecting through the opening 17. The revenue stamp is indicated at 20. It is placed across the top of the neck of the metal container, down the sides thereof and along the shoulder so that it may be cemented to the lugs 18 and 19. The lugs are practically the same width as the revenue stamp so that the revenue stamp may be cemented thereto all the way across the underface thereof.

From the above it will be apparent that a container has been provided for distilled liquors wherein the glass receptacle is completely housed within the metal receptacle, the parts of which are seamed together, and the only way in which access may be had to the contents of the inner receptacle, is through a tearing strip which ruptures the metal, and thus destroys the container. The revenue stamp is applied to the outer face of the metal receptacle so that it is visible for

ready inspection. At the same time, the revenue stamp is secured to the glass bottle within, so that the glass bottle cannot be removed from the metal container without the rupturing of the revenue stamp.

5 It is obvious that minor changes in the details of construction and the arrangement of the parts may be made without departing from the spirit of the invention as set forth in the appended claims.

10 Having thus described the invention, what I claim as new and desire to secure by Letters Patent, is:

15 1. A container for distilled liquors comprising an inner receptacle of glass or the like having a neck portion and a shoulder portion, an outer metal receptacle having the parts thereof seamed together and substantially conforming in shape to said inner receptacle so as to fit the neck and shoulder portion thereof, said metal receptacle having openings therethrough positioned in the 20 region adjacent the shoulder of the glass receptacle and dimensioned so that a revenue stamp

applied to the outer face of the metal receptacle may also be attached to said inner receptacle so as to prevent the separation of the receptacles and the opening of the inner receptacle without rupturing said revenue stamp.

2. A container for distilled liquors comprising an inner receptacle of glass or the like having a neck portion and a shoulder portion, said shoulder portion having integral projecting lugs, an outer metal receptacle having the parts thereof seamed together and substantially conforming in shape to the inner receptacle, said metal receptacle having openings therethrough in the neck portion thereof through which the lugs of the inner receptacle project so that a revenue stamp applied to the outer face of the neck of the metal receptacle may be attached to said lugs and thus prevent the separation of the receptacles and the opening of the inner receptacle without rupturing said revenue stamp.
